Specification for Design.

Patented June 6, 1916.

Application filed February 15, 1916. Serial No. 78,540. Term of patent 7 years.

To all whom it may concern:

Be it known that I, FREDERICK KIEHLER, a citizen of the United States, and resident of Detroit, in the county of Wayne, in the State of Michigan, have invented a new, original, and ornamental Design for Vehicle-Bodies, of which the following is a specification, reference being had to the accompanying drawings forming part hereof, and in which:

Figure 1 is a side elevation of a vehicle body built according to my design; and Fig. 2 is a rear view thereof.

I claim:

The ornamental design for a vehicle body, substantially as shown.

In testimony whereof I affix my signature.

FREDERICK KIEHLER.
